UNITED STATES PATENT OFFICE.

RICHARD BAER, OF NEW YORK, N. Y.

PERMUTATION-LOCK.

1,391,357.

Specification of Letters Patent. Patented Sept. 20, 1921.

Application filed May 19, 1920. Serial No. 382,645.

To all whom it may concern:

Be it known that I, RICHARD BAER, a citizen of Czechoslovakia, and resident of the borough of Manhattan, in the city, 5 county, and State of New York, have invented certain new and useful Improvements in Permutation-Locks, of which the following is a description.

The present invention relates to improvements in permutation locks, and has for its 10 object to provide a lock adapted for use upon ordinary house doors or the like, and which may be operated with facility by one knowing the combination of the same.

15 I further propose to provide a novel type of key adapted to coöperate with the lock to bring the several parts thereof into proper relation to permit opening of the door so that the invention provides at once a 20 lock which may be opened by a key, and may also be opened without a key, and by any one familiar with the combination.

A further object is to provide a lock 25 which may be readily operated from one side of the door without the manipulation of the permutation means, and which will automatically lock itself when the door is closed.

Other objects are to provide a lock which 30 will not readily get out of order, which will be simple and economical in construction, and practicable for house door use. It is further proposed to enable the changing of the combination whenever desired.

35 With these and other objects in view, embodiments of my invention are shown in the accompanying drawings, and these embodiments will be hereinafter more fully described with reference thereto, and the invention will be finally pointed out in the 40 claims.

In the accompanying drawings:

Figure 1 is a front elevation of the adjacent portions of a door and door jamb provided with a lock according to one embodiment of my invention.

Fig. 2 is a horizontal sectional view taken along the line 2—2 of Fig. 1.

Fig. 3 is a perspective view of a portion 50 of the keeper, and showing the bolt means thereon projected.

Fig. 4 is a similar view showing the bolt means held in retracted position, and showing the relation of a portion of the lock 55 about to be closed thereon.

Fig. 5 is a perspective view of the key.

Fig. 6 is a plan view showing the manner of engagement of the key with the lock.

Fig. 7 is a front elevation of a door and door jamb provided with a modified form 60 of my invention.

Fig. 8 is a horizontal sectional view taken through the top of the lock casing of Fig. 7.

Fig. 9 is a side view of the keeper employed in this embodiment.

Similar reference characters indicate corresponding parts throughout the several figures of the drawings.

Referring to the drawings, and more particularly to Figs. 1 to 4 thereof, the embodiment of my invention shown therein comprises a cylindrical casing 10, having a flange 11 adapted to be secured to the inner side of the door by screws or the like 12, and provided at its upper face with an extension 13, having projecting portions 14 and 15 bent at right angles thereto, and in parallel relation to each other, and adapted to embrace the casing 16 of the keeper, said casing being provided at its lower side with 80 flanges 17 and 18 secured to the door jamb by means of screws 19. An opening 20 is provided in the wall of the casing 10 in alignment with the opening of the keeper 16, and adapted, as will presently more fully appear, 85

to receive the bolt of the keeper. A stationary shaft 21 extends axially of the casing 10, and through an opening 22 provided in the door. At its inner end the shaft is provided with a squared portion 23, engaging a correspondingly shaped hole 24 in the casing to prevent rotation of the shaft, and upon a screw-threaded extension 25 of the shaft there is provided a retaining nut 26. At its forward end the shaft is provided with a 90 semicircular recess 27 disposed inwardly of the forward end of a sleeve 28, mounted upon the shaft, and upon the inner end of which there is fixedly mounted the hub 29 of a disk 30. Upon the sleeve 28 there is provided a 95 second sleeve 31, its outer end terminating inwardly of the end of the sleeve 28, while upon its inner end there is fixedly secured the hub 32 of a disk 33, and similarly upon the sleeve 31 there is mounted a sleeve 34, 100 terminating inwardly of the end of said sleeve 31, and having fixedly secured to its inner end the hub 35 of a disk 36. Upon the sleeve 34 there is mounted a fourth sleeve 37 terminating inwardly of the end of said sleeve 34, and having secured to its inner end 105 the hub 38 of a disk 39. A cone-shaped

collar 40 surrounds the sleeve 37 at the outer side of the door, and is secured to the door by screws 41, and is provided with an index marking 42 at its upper side, adapted to co-operate with graduated markings 43 provided upon the exposed ends of the several sleeves 28, 31, 34 and 37, and which are suitably numbered so that by turning the sleeves to a predetermined relation with the index 42, the several disks 30, 33, 36 and 39 may be brought to a predetermined relation in which the respective cut-out portions 44, 45, 46 and 47 will be brought in alinement at the opening 20 of the casing, and in which position the door is free to be opened, as will presently more fully appear.

Within the casing 16 of the keeper there is provided a slideable bolt 48, having a plunger rod 49 extending through an opening 50 in the rear wall of the casing and provided at its end with a knob 51, a spring 52 disposed between the end of the keeper and the end of the casing upon the plunger rod adapted to normally project the bolt forwardly. At the forward end of the bolt there are provided a series of teeth 53, 54, 55 and 56, adapted to be projected through the opening 20 of the casing 10 and enter between the several permutation disks and providing cutouts between the teeth to receive the disks, and in the position of the disks when the cut-out portions thereof are not all in alinement with the opening 20, such engagement of the keeper locks the door. By turning the disks into the proper relation to aline the cut-out portions at the opening 20, the keeper is free to permit opening of the door and free passage of the keeper through the several cut-outs, and through a cut-out 57 provided in the base of the casing 10. The bolt 48 may be retracted from the inner side of the door by means of the knob 51 of the plunger rod 49, thereby permitting the door to be opened.

In the upper side of the casing 16 of the keeper and close to the forward open end thereof, there is provided a pivoted catch 58, having a trip portion 59 projecting above the upper surface of the casing, and a retention portion 60 disposed in a slot 61, the catch adapted, when the bolt is retracted, to drop by gravity in front of the bolt, and thereby retain the same in retracted position, so that the door can be opened after the hand is removed from the handle 51. In closing the door the portion 15 of the casing 10, which embraces the casing of the keeper, engages the trip portion 59 of the catch, as indicated in Fig. 4, as the door comes to complete closed position, raising the catch and releasing the bolt 48 so that the same projects into locking relation with the disks.

In Figs. 5 and 6 I have illustrated a novel type of key adapted to be used in coöpera-

tion with my improved lock, and which comprises a shank 62 of such size as to be inserted within the sleeve 28, and provided at its end with a semicircular cut-out 63 adapted to permit interlocking of the end 70 of the shank with the end of the shaft 21, provided with a corresponding shaped cut-out, as shown in Figs. 6 and 7 and upon the shank relatively near its outer end there is provided a lug 64 adapted to engage a cut-out 65 in the end of the sleeve 28, so disposed as to bring the disk 30 into such position that its cut-out portion 44 is in alinement with the cut-out 20 when the shank of the key is interlocked with the shaft, and the lug 64 is engaged with said cut-out. Upon the end of the shank there is provided a collar 66, having a series of fingers 67, 68 and 69 pivotally mounted thereon, the finger 67 being shortest in length, and adapted to be swung into engagement with a cut-out 70 provided upon the end of the sleeve 31, while the finger 68 is adapted to be engaged with a cut-out 72, provided upon the end of the sleeve 34, and similarly, the finger 69 is adapted to be engaged with a cut-out 73 provided upon the end of the sleeve 37. The relation of these fingers, it will be understood, is predetermined, and is such that when they are engaged with the several sleeves, the sleeves are turned so that the disks carried thereby are brought into such relation that the several cut-out portions thereof register with each other and with the openings 20 and 57 of the casing 10, and in which position, as above pointed out, the lock is inoperative to retain the door closed. This key provides a very convenient means for operating the permutation lock, and at the same time the lock may also be operated without its use by any one who knows the proper combination. The combination of the lock may be conveniently changed without removing the casing, by changing the position of disks upon the sleeves, and to this end there are provided set screws 74 in the hubs of the several disks which may be engaged by a screw driver through the opening 20.

In Figs. 7 to 9 I have illustrated an embodiment which comprises a rectangular casing 75, provided with a flange 76 secured to the inner side of the door by screws 77, and having provided therein a shaft and a series of concentrically superimposed sleeves similar to those shown in the first form of my invention, and which are, therefore, correspondingly numbered. In substitution of the disks there are provided in the present modification, a plurality of gears 78, 79, 80 and 81, their hubs 82, 83, 84 and 85 being secured by set screws 86 to the several sleeves. In the lower portion of the casing there are slidably mounted a plurality of bolts 87, 88, 89 and 90, having rack 130

teeth at their upper sides, meshing with the respective gears, the bolts being guided at their forward ends through openings 91 provided in the forward face of the casing, and at their rear ends by lugs 92, pins 93, provided upon the ends of the bolts, engaging the lugs in the fully projected position of the bolts, and thereby limiting their outward movement. Upon the jamb of the door there is provided a keeper comprising an arm 94, having a base plate 95 secured to the jamb by screws 96, said arm being provided in its lower side with cut-outs 97, 98, 99 and 100, adapted to be engaged by the respective bolts 87, 88, 89 and 90, and thereby lock the door, and in the bolts there are provided a series of cut-outs 101, 102, 103 and 104, which, when the bolts are brought to a predetermined relation by manipulation of the permutation means, are alined, and embrace the keeper, so that the keeper is free to be disengaged therefrom upon opening the door.

I have illustrated and described preferred and satisfactory embodiments of my invention, but it is obvious that changes may be made therein, within the spirit and scope thereof, as defined in the appended claims.

I claim:

- 30 1. In a lock, a casing, a shaft on said casing, a plurality of superimposed relatively rotatable sleeves upon said shaft, a plurality of locking members operatively connected to the respective inner ends of said sleeves, and disposed in spaced relation to each other, the outer ends of said sleeves being exposed to permit of independent operation thereof to bring said locking members to predetermined relation with each other, said members being provided with cut-outs adapted to be alined in said predetermined relation, and a keeper provided with a plurality of spaced portions adapted to be disposed in the spaces between said locking members, and adapted to be released from engagement with said locking members upon alinement of said cut-outs in said predetermined relation.
- 45 2. In a lock, a casing, a shaft in said casing, a plurality of superimposed relatively rotatable sleeves upon said shaft, a plurality of locking members operatively connected to respective inner ends of said sleeves, the outer ends of said sleeves being exposed to permit of independent operation thereof to bring said locking members to predetermined relation with each other, said members being provided with cut-outs adapted to be alined in said predetermined relation, a keeper comprising a casing, a bolt disposed in said casing, and adapted to be projected and retracted, said bolt adapted to lockingly engage said locking members in the projected position, and adapted to be retracted to
- 55 release the same from said locking members, and adapted in the projected position, to be released upon alinement of said cut-outs in said predetermined relation.
- 65 3. In a lock, a casing, a shaft in said casing, a plurality of superimposed relatively rotatable sleeves upon said shaft, a plurality of locking members operatively connected to respective inner ends of said sleeves, the outer ends of said sleeves being exposed to permit of independent operation thereof to bring said locking members to predetermined relation with each other, said members being provided with cut-outs adapted to be alined in said predetermined relation, a keeper comprising a casing, a spring-pressed bolt disposed in said casing, and adapted to be projected and retracted, said bolt adapted to lockingly engage said locking members in the projected position, and adapted to be retracted to release the same from said locking members, and adapted in the projected position, to be released upon alinement of said cut-outs in said predetermined relation, a trip catch pivotally mounted upon said casing, and adapted to retain said bolt in retracted position, and means carried by said first-mentioned casing, and adapted to engage said trip catch upon movement of said first-mentioned casing into locking relation with said casing of said keeper to disengage said catch to permit projection of said bolt.
- 75 4. In a lock, a casing, a stationary shaft in said casing, a plurality of superimposed relatively rotatable sleeves upon said shaft, a plurality of locking members operatively connected to the respective inner ends of said sleeves, the outer ends of said sleeves being exposed to permit of independent operation thereof to bring said locking members to predetermined relation with each other, the outer ends of said sleeves being provided with cut-outs adapted to be alined in said predetermined relation, a keeper adapted to engage said locking members, and adapted to be released upon alinement of said cut-outs in said predetermined relation, interlocking means at the outer end of said fixed shaft, key engagement means at the outer ends of said sleeve, and a key comprising a shank adapted to be interlocked with said interlocking means of said shaft, means on said key adapted to engage said key engagement means of one of said sleeves, and means on said key adapted to be engaged with said key engaging means of said other sleeve by turning of said sleeves to bring said locking members into predetermined position.
- 85 5. In testimony that I claim the foregoing as my invention, I have signed my name.

RICHARD BAER.
